CLAIM

The ornamental design for a microphone, as shown and described.

DESCRIPTION

FIG. 1 is a front view of a microphone showing my new design;

FIG. 2 is a left side view thereof;

FIG. 3 is a back view thereof;

FIG. 4 is a right side view thereof;

FIG. 5 is a perspective view thereof;

FIG. 6 is a top view thereof; and,

FIG. 7 is a bottom view thereof.

The broken lines shown in FIGS. 1-5 and 7 illustrate portions of the microphone that form no part of the claimed design.
